UNITED STATES PATENT OFFICE.

BENJAMIN F. BRAMBLETT, OF HOUSTON, TEXAS.

GATE-LATCH.

1,359,788.

Specification of Letters Patent. Patented Nov. 23, 1920.

Application filed December 15, 1919. Serial No. 345,127.

To all whom it may concern:

Be it known that I, BENJAMIN F. BRAMBLETT, citizen of the United States, residing at Houston, in the county of Harris and State 5 of Texas, have invented certain new and useful Improvements in Gate-Latches, of which the following is a specification.

This invention relates to new and useful improvements in a gate.

10 One object of the invention is to provide a gate of the character described having an improved form of hinge for swinging the same to one post and also equipped with an improved form of latch for securing the 15 gate in a closed position.

With the above and other objects in view, the invention has particular relation to certain novel features of construction, operation and arrangement of parts, an example 20 of which is given in this specification and illustrated in the accompanying drawing wherein:

Figure 1, is a side view of the gate.

Fig. 2 is an enlarged, vertical, sectional 25 view, taken on the line 3—3 of Fig. 1.

Referring now more particularly to the drawings wherein like numerals of reference designate similar parts in each of the figures, the numeral 1 refers to the gate 30 post to which the gate is swung and the numeral 2 refers to the gate. The gate is swung to the post 1 by means of an upper hinge, consisting of a hook 3, which projects out from the post, and an eye 4 operating 35 thereover, and which is carried by the gate and by a suitable lower hinge 5. A strong coil spring 11 is secured at one end to said post and its other end to a hinge 5.

Spaced from the post 1 there is the other 40 post 12 to which the free edge of the gate may be secured and from which it may be released through the mechanism now to be described. Secured to the inner side of said post 12 there is a latch casing 13, having an 45 oblong vertical slot therethrough and in this slot work the latches 14, 14, whose upper ends have the respective vertical slots 15, 15, which have bearings on the transverse pins 16, the walls of said casing acting as stops 50 limiting the outward movement of said latches. Mounted upon the post 12 there is a lever 17, whose inner end is connected to said respective latches by means of the

chains 18; 18. The free edge of the gate has a projection 19, which normally extends between said latches and holds the gate closed. When it is desired to open the gate the outer end of the lever 16, is depressed, which will operate through the chains 18 to lift the latches 14 out of the range of the projection 19 and said gate may then be swung open in either direction. When the gate is released the tension of the spring 11 will cause it to swing shut and in so doing the projection 19 will first strike against the outer side of one 65 of the latches 14 and the same will swing inwardly permitting the gate to pass and will then drop behind said projection 19 but the gate will be stopped by the projection 19 striking against the other latch 14 and the 70 gate will then be retained between said latches until it is desired to again open the same.

A rod 20 is pivoted at its upper end to the outer end of the lever 16 and its lower end 75 extends through a bearing 21, carried by the post 12 and is turned outwardly forming a foot pedal 22. The rod has a collar 23 fastened thereon above the bearing 21 and surrounding said rod and interposed between 80 the bearing 21 and the collar 23 is a coil spring 24. By depressing the pedal 22 the latches 14 will be elevated through the mechanism described and when the pedal is released, the spring 24 will operate to elevate 85 the rod 20 which will permit said latches to drop into active position.

What I claim is:

The combination with a swinging gate whose free edge carries an extension, of a 90 post, a latch-casing carried by said post, two latches pivoted in and depending from the casing and embracing said extension, when the gate is in closed position to retain it in said position, stops limiting the outward 95 movement of said latches and a manual device for elevating the latches out of the path of said extension to permit said gate to be opened.

In testimony whereof I have signed my 100 name to this specification in the presence of two subscribing witnesses.

BENJAMIN F. BRAMBLETT,
